175,532

BUMPER FOR AN AUTOMOBILE

Paul W. Buechler, Royal Oak, Mich., assignor to General Motors Corporation, Detroit, Mich., a corporation of Delaware

Application December 16, 1954, Serial No. 33,585

Term of patent 7 years

(Cl. D14—6)

Fig. 3

Fig. 4

Figure 1 is a front perspective view of a bumper for an automobile, showing my new design;

Figure 2 is a top plan view of the bumper;

Figure 3 is a fragmentary view taken on the plane indicated by line 3-3 in Figure 1; and

Figure 4 is a side elevational view of the bumper.

The fragmentary portion of the automobile and spare tire shown by means of broken lines are disclosed for

I claim:

The ornamental design for a bumper for an automobile, substantially as shown and described.
